Fig. 1

Fig. 2

Fig. 4

FIG. 1 is a side elevational view of a hat showing my new design;

FIG. 2 is a rear perspective view thereof;

FIG. 3 is a bottom perspective view; and

FIG. 4 is a top plan view thereof.

The characteristic feature of my design resides in the brim portion at the back, wherein the brim is of double thickness, the brim portion from the right being superimposed on the portion from the left all as shown in full lines on the drawing.

I claim:

The ornamental design for a hat, as shown and described.
